[57] **CLAIM**

The ornamental design for a drill, as shown and described.

DESCRIPTION

FIG. 1 is a perspective view of a first embodiment of a drill showing our new design;
FIG. 2 is a left side elevational view of the first embodiment;
FIG. 3 is a right side elevational view of the first embodiment;
FIG. 4 is a front elevational view of the first embodiment;
FIG. 5 is a rear elevational view of the first embodiment;
FIG. 6 is a top plan view of the first embodiment;
FIG. 7 is a bottom plan view of the first embodiment;
FIG. 8 is a perspective view of a second embodiment of a drill showing our new design. The chuck is shown in dotted lines and forms no part of our new design;
FIG. 9 is a left side elevational view of the second embodiment. The right side elevational view is identical to the first embodiment shown in FIG. 3;
FIG. 10 is a bottom plan view of the second embodiment;
FIG. 11 is a top plan view of the second embodiment;
FIG. 12 is a front elevational view of the second embodiment; and,
FIG. 13 is a rear elevational view of the second embodiment. The broken line showing of a chuck in the figures is for illustrative purposes only and forms no part of the claimed design.
